UNITED STATES PATENT OFFICE

2,209,124

AUTOMATIC WATER GATE OPERATOR

Benjamin H. Kooken, Veradale, Wash.

Application May 20, 1939, Serial No. 274,827

3 Claims. (Cl. 137—145)

This invention relates to irrigation systems of the overhead sprinkler type, and among the objects of the invention are the provision of means for using the full flow of water on various sections at regular and shorter intervals thus providing a greater benefit of the land irrigated; to conserve the water in comparison with the present method of ditching which has proven so destructive and wasteful; and to irrigate more economically.

The invention together with its objects and advantages will be best understood from a study of the following description taken in connection with the accompanying drawings wherein:

15 Figure 1 is a side elevational view illustrating the application of the invention.

Figure 2 is a view taken substantially on the line 2—2 of Figure 1.

Figure 3 is a top plan view, and

20 Figure 4 is a detail view partly in section and partly in elevation illustrating certain details hereinafter more fully referred to.

Referring more in detail to the drawings it will be seen that the water supply pipes of the 25 irrigation system are indicated by the reference numerals 22—22.

Rising from the supply pipes 22, in accordance with the present invention, are stand pipes 3—3. At the lower ends thereof the stand pipes 3 extend 30 into the water supply pipes 22 and are positively secured to the water supply pipes 22 through the medium of clamps 2—2 of any suitable construction.

Also, extending between the clamps 2 and secured at the ends thereof to the clamps in any suitable manner is a brace rod 1.

Also the stand pipes 3—3 are braced with respect to one another through the medium of cross braces 4—4.

40 Disposed between the stand pipes 3—3 above the braces 4—4 is a cross-bar 5 while secured to the upper ends of the stand pipes 3 and extending between said stand pipes is a cross-bar 12.

Extending between the cross-bars 5 and 12 in 45 parallelism with the stand pipes 3 are guide rods 11—11.

The rods 11 cooperate with the stand pipes 3 for guiding in vertical movement, water receptacles or buckets 9—9.

50 Each bucket 9 is provided at diametrically opposite sides thereof with guide rings 13 and 14, the series of rings 13 on each bucket slidably embracing a guide rod 11, and the series of rings 14 on each bucket slidably embracing a stand pipe 3 as shown.

Each of the buckets 9 is provided in the bottom thereof with a drain opening controlled by a ball check-valve 7 accommodated within a cage 8 provided within the bucket at the bottom thereof and integral with the bottom of the 5 bucket.

For each ball check-valve 7 there is mounted on the cross-bar 5 an upwardly extending valve-displacement stud or pin 6, as also clearly shown in Figure 4. It will thus be seen that as a water bucket or receptacle 9 moves downwardly the ball valve 7 will be engaged by the displacement stud 6 causing the ball 7 to unseat and thus permit the water in the lowered receptacle 9 to drain therefrom.

Arranged in each water supply pipe 22 are vertically slidable gate valves 21 and the valves 21 of each pair are connected by a rod 23.

A bucket or receptacle 9 is provided for each pair of gate valves so that as one of the buckets 20 9 moves downwardly in response to the weight of the water therein, that pair of gate valves will be lowered to closed position. As one of the buckets moves downwardly to so close one pair of gate valves the other bucket, from which the water has drained, will move upwardly for causing the gate valves connected therewith to move up into open position.

The invention further includes a rocker arm 17 that is pivoted as at 18 to a relatively short 30 standard 19 secured to and rising from the upper cross-bar 12. At the ends thereof the rocker arm 17 is provided with lug-equipped caps 20, and each cap 20 is connected to a series of guide rings 14 associated with a bucket 9 through the 35 medium of a link 24 that is pivotally connected to a rod 25 that in turn is secured to the rings 14 as shown.

Also each cap 20 is connected with a pair of gate valves 21 through the medium of rods 26.

At the upper end thereof each stand pipe 3 is provided with a faucet 27, and each faucet 27 is set or adjusted to allow sufficient water to flow into a bucket 9 to cause said bucket to move downwardly. Thus by adjusting each faucet 45 the period of time between the opening and closing movements of each set of gate valves can be regulated and it is necessary to use a pair of valves in each supply line 22, with one valve to one side of the stand pipe 3 and the other valve to the opposite side thereof so as to prevent return water from the nozzle side of the line 22 from flowing back into the stand pipe 3 and then into the bucket which, of course, would interfere with the operation of the device. By 55

having the two valves 21 each pipe 22 is closed to a stand pipe 3 at both sides of the stand pipe.

As before described, and as believed to be apparent from the foregoing, as one bucket 9 moves downwardly rocker 17 will be caused to rock so as to close the gate valves that are connected with the rocker arm 17 at that end of the rocker arm to which the downwardly moving bucket is connected, and at the same time cause the bucket from which the water has drained to raise, and consequently cause the gate valves connected with the end of the rocker arm to which the last-named bucket is connected to move upwardly to open position. Thus it will be seen that as one pair of gate valves is caused to open the other pair is caused to close. As a result the full flow of water on various sections at regular and shorter intervals is utilized to the end that the irrigation of the land will be more economically effected in comparison with the present method of ditching.

It is thought that a clear understanding of the construction, utility and advantages of an invention of this character will be had without a more detailed description; the invention, in actual practice, and in addition to being used for land irrigation, may be used with facility for the control of orchard pests such as codling moths, red spider, wooly aphis, two-spotted mite, brown mite, and the like by maintaining the trees of the orchard washed with water continuously, thereby preventing the pests from hatching and working on such trees.

Having thus described the invention what is claimed as new is:

1. In a device of the class described, a pair of liquid supply pipes, valve means for controlling the supply of liquid to each pipe, vertically movable buckets associated with each pipe, discharge means for each pipe for directing liquid from each pipe into a bucket when the valve means of said pipe are opened, means for operating the valve means by vertical movement of the buckets, a valve controlled outlet in the bottom of each bucket, means for opening said valve when the bucket reaches its limit of downward movement and means for connecting the buckets

together to cause downward movement of the filled bucket to raise the other bucket.

2. In a device of the class described, a pair of stand pipes, means for connecting said pipes to a supply of liquid, valve means for controlling the flow of liquid to each stand pipe, an upright adjacent each stand pipe, a bucket located between each stand pipe and upright, and guided for vertical movement by said stand pipe and upright, a spigot at the upper end of each stand pipe for leading liquid from the stand pipe into the bucket associated therewith, a valve controlled opening in the bottom of each bucket, a projection for opening the valve of said opening when the bucket reaches its limit of downward movement, a rocker bar, means for supporting the same, means for connecting one end of the bar to one bucket, means for connecting the other end of the bar to the other bucket, and means for actuating the valve means of the stand pipes by movement of the bar for opening said valve means when a bucket is in raised position and closing said valve means when said bucket is in lowered position.

3. In a device of the class described, a pair of flow pipes, a pair of valves in each pipe, a stand pipe connected with each flow pipe between the valves, a vertically movable bucket located adjacent each stand pipe, a faucet at the top of each stand pipe for leading liquid from the stand pipe into the bucket associated therewith, a valve controlled opening in the bottom of each bucket, means for opening said valve of the opening when the bucket reaches the limit of its downward movement, a rocker bar supported for rocking movement above the buckets, means for connecting the ends of the bar to the buckets for causing downward movement of one bucket to raise the other bucket, and means for connecting the ends of the bar to the first-mentioned valves for opening said valves in one flow pipe when the bucket adjacent said flow pipe is in raised position and closing the valves in the other pipe, the position of the valves in the respective pipes being reversed when the position of the buckets is reversed.

BENJAMIN H. KOOKEN.
